UNITED STATES PATENT OFFICE.

IONA WILKINSON, OF LIGONIER, INDIANA, ASSIGNOR TO WILKINSON QUILT COMPANY, OF LIGONIER, INDIANA, A CORPORATION OF INDIANA.

DESIGN FOR A BEDQUILT.

47,479.

Specification for Design.

Patented June 15, 1915.

Application filed April 10, 1915. Serial No. 20,581. Term of patent 7 years.

To all whom it may concern:

Be it known that I, IONA WILKINSON, a citizen of the United States, residing in Ligonier, in the county of Noble, State of Indiana, have invented a new, original, and ornamental Design for a Bedquilt, of which the following is a specification, reference being had to the accompanying drawing, forming a part thereof.

The figure is a plan view of a bed quilt, illustrating my new design.

I claim:

The ornamental design for a bed quilt as shown.

IONA WILKINSON.

Witnesses:

MAURICE BRUBAKER,
CHAS. H. SIMMONS.
